UNITED STATES PATENT OFFICE.

EDWARD A. WALLER, OF CHICAGO, ILLINOIS.

COLOR-PRINTING COMPENSATOR.

Application filed November 22, 1924. Serial No. 751,594.

This invention relates to printing presses of the kind known as web presses, and especially to multi-color printing by multiple web presses, in which the several webs 5 are split apart from a common roll as they feed into the press. The main objects of the invention are to provide means of improved form and better adapted to assure proper registry of the successive colors as the paper 10 passes through the press; to provide improved means for manually adjusting and controlling the webs and more especially the compensator rolls; to provide for eliminating substantial space between the edges of 15 the adjacent webs; to provide for ready gag- ing and visual observation of the precise setting of each compensator roll; to provide an improved form of mounting for the rolls; to provide in a multiple web press a com- 20 mon compensator roll for each mutually cor- responding group of printing cylinders, and supplementary thereto a group of individual compensators, one for each printing cylin- 25 ders; to provide for coaxial mounting and concentric adjustment of the supports for the short rolls; and to provide for prevent- 30 ing and eliminating wrinkles in the paper as it passes through the press.

An illustrative embodiment of this invention is shown by the accompanying drawings, in which—

Figure 1 is a diagrammatic side view of that part of a four color printing press to which this invention relates and shows con- 35 ventionally the course of the web through the rolls.

Figure 2 is an enlarged view of the gage and control means for the compensator rolls.

Figure 3 is a similar view of a modified 40 form of gage and control means, differing somewhat from the device of Figure 2.

Figure 4 is mainly a vertical axial section through the alined cylindrical mountings for the short compensator rolls, on the line 4—4 45 of Figure 3, with the compensator rolls all in side elevation.

Figure 5 is a similar view of the device shown by Figure 2, the section being on the line 5—5 of said figure.

Figure 6 is a still further enlarged view 50 of one of the short compensator rolls shown in Figure 5, as it appears in axial section.

In the construction shown in the draw- 55 ings, referring first to Figure 1, the multiple web printing press which as a whole is not shown, includes a plurality of printing

cylinders 1 arranged in series to print on a strip of paper or web 2, platens 3 one for each cylinder, web carrying rolls 4, one on each side of each cylinder, a single full 60 length multiple web compensating roll 5 disposed in front of each printing cylinder for establishing the main adjustment, and a plurality of short compensating rolls 6 ar- 65 ranged in axially alined groups between each main roll 5 and the corresponding set of alined printing cylinders, one in each group for each web of paper being fed through the press. Provision is made for mounting a supply roll 7, in due relation to the press 70 for splitting and feeding parallel web sections over carrying rolls 8 disposed between the supply roll 7 and the first corresponding main compensators 5.

Referring now to the specific embodiment 75 of Figures 2 and 5, each main compensating roll 5 is provided with adjusting means 9 and an index gage 10, as shown on the left side of Figure 2, and separate adjusting and gage means are provided for each short roll, 80 as shown on the right hand side of said Figure 2.

The common compensator 5 is mounted rotatably on an axial shaft 11, which in turn is carried on a pair of arms 12 disposed at the ends. The side arms 12 are fixed co- 85 turnably on a rocker shaft 13, the ends of which are journaled at 14 on the frame of the machine, said shaft 13 projects beyond the frame on the control side, as shown at 15 90 in Figure 5. On the outer tip of this shaft is fixed a bevel gear 16 arranged to coact with a similar gear 17 fixed on the upper end of a control shaft 18, the lower end of which is provided with a hand wheel 19. 95

Clockwise turning of hand wheel 19 re- 100 sults in clockwise swinging of the arm 12 and roller 5, as viewed from the left side of Figure 5, and vice versa. The resultant ad- justment and effect on the web 2 as accom- modated by this movement is apparent from Figure 1. In order that the operator may readily determine the position of roller 5 without direct inspection thereof, a gage dial 10' is mounted on the frame supported 105 bracket 20 in due relation to index finger 21 fixed on shaft 15 adjacent the gear 16.

In order to prevent endwise swinging and vibration of shaft 11 and roll 5 friction 110 bearings 22 are provided on the press frame opposite arms 12 to bear thereon. Each member 22 has a hand operated setting lever

22'. Each arm 12 has an arcuate bearing segment 12' to accommodate variable setting contact with the damper 22.

Referring now to the short compensator rolls 6 (Figures 2 and 5), each of these rollers is carried rotatably by a pair of arms 23 which in turn are fixed on a shaft 24 or 25, one shaft being provided for each roller. The shafts 24 support the outer rolls 10 and the shafts 25 support the inner rolls, said shafts 24 and 25 all being arranged end to end in coaxial alinement and each being rotatable, independent of the others. In order to minimize friction, roller bearings 15 therefor are provided as at 26. Control means for the two left hand rolls are provided at the left hand side, as shown on Figure 5, and similar control means are provided at the right for the right hand rollers. 20 Each of the outer shafts 24 is provided with an extension 24' on the outer end of which is fixed a bevel gear 27. Coacting with said gear is a similar gear 28 fixed on the upper end of a vertical shaft 29, the lower end of 25 which is provided with a manual control handle 30. Clockwise turning of the handle 30 results in counter-clockwise swinging of arms 23 and the roller 6 carried thereby, as viewed from the left of Figure 5 and vice versa. Hence it should be noted that the handles 19 and 30 when turned clockwise co-operate to slacken the web 2 and vice versa, and that thus turning either of said handles alone also tends to slacken the web. 30

35 The two inner rolls 6 are operated by a slightly different mechanism. In this instance the corresponding shafts 25 have fixed medially thereof a pinion 31 coacting with which is a similar pinion 32 each mounted 40 on one of a pair of axially alined shafts 33. On the outer end of each shaft 33 is a bevel gear 34 with which coacts a similar bevel gear 35 fixed on the upper end of a shaft 36 on the lower end of which is fixed a hand 45 wheel 30. The swinging of the two inner rolls 6 corresponds with the appropriate hand wheels 30 in like manner as the two outer rolls.

50 In order to avoid spacing the rolls and corresponding webs apart and to accommodate the arms 23 accordingly, each of the rolls 6 is made in two or more axial parts, one of which is relatively short as shown at 6', the outer rolls each having one such part and each inner roll two such parts one at each end. Moreover in order to permit removing the inner part of a roller face, as sometimes is desirable to remove web wrinkles, these rolls may be made in sections, as 55 shown in Figure 6. The tubular shaft 6'' receives the parts of the axially sectional roller. The middle roller part 6^a is here made in two sections 6^a each secured to the shaft 6'' by a screw 6^c. On each side of the 60 part 6^a is a roller part 6^d. Next to sections

6^d come the arms 23 and then the parts 6^e come at the ends.

Each rocker shaft 24 and 33 is provided with an index finger 37 duly related to a corresponding gage dial segment 38, similar to the indicator means provided for the long roll 5.

Referring now to the modified constructions shown in Figures 3 and 4, the main compensator roll 5 is formed and mounted as in Figures 2 and 5, but the friction damper 40 is provided with a compression spring 41 to assure sufficient pressure instead of relying on an adjustable hand control means for setting. Here also the rocker bar 75 13 on which the arms 12 are set is controlled by a crank arm 42 fixed to the left end as viewed in Figure 4. The outer end of arm 42 is secured loosely to a thrust control rod 43 having adjustable screw connection to the press frame at 44. The upper end of rod 44 receives the perforated tip of arm 42 which is secured adjustably and loosely between the two nuts 45. The lower end of rod 44 is provided with a hand wheel, not shown, substantially the same as on rod 18 of Figure 2. Clockwise turning of said rod 43 by its hand wheel swings roller 5 to the left, as viewed in Figure 3, whereby web tension is increased 90 and vice versa.

95 A gage 10' and index finger 21 are provided for shaft 13 substantially as in Figures 2 and 5.

Referring to the short compensator rolls 6, they are each constructed, arranged and supported as in Figure 4 on arms 46. These arms are mainly similar to the arms 23 except at the hubs, which are progressive in size from right to left, as viewed in Figure 4, to accommodate the sleeve system now to be described. The rollers 6 are all supported on a common shaft 47 journaled on the frame at 48 and 49. The right most roller has its arms fixed directly on said shaft 47, which at the left end is provided with a crank arm 50 for control substantially as for shaft 13. Said arm is connected to a rod 51 which at its lower end below its screw mounting at 52 is provided with a hand wheel, not shown. Clockwise turning of rod 51 swings the corresponding roller 6 to the right and so increases the web tension. 100 105 110 115 120

125 The next roller 6 has its arms 23 fixed to a relatively short cylindrical rocker shaft 54 fitting snugly but rotatably upon shaft 47. The left end of shaft 54 terminates just short of the lever connection on shaft 47, and is provided with a control arm 55 similar to arm 50. Said arm 55 is connected to another thrust rod 51 similar to that for shaft 47. In like manner the third roller 6 is carried by a still shorter overlying concentric rocker cylinder 56, which is also controlled by a crank arm and thrust rod such as above described. The fourth and left roller 6 is car- 130

ried by a still larger concentric rocker cylinder 57 having similar crank arm and thrust rod control means, as will be understood. Each of the cylinders is provided with gage and index means substantially as for rod 47.

The feature about this invention which I especially emphasize is that the full width common sheet is divided as it enters the press into four parallel webs and that as these webs advance through the press they do not diverge, but the edges are still operating close together over the long and then the short rollers, from one color to a succession of other colors. With one operation it assures perfect register and that means an enormous saving of waste. When the webs are once in register the clutches 22 or 40 against the compensator are locked and the dial indicators are on their true marks until the end 20 of the run.

This process is a distinct practical improvement over the old method of great variation and uncertainty on multicolor work. I have improved this process of color printing with the elimination both of folder waste and practically all wrinkles. This improvement is due largely to the compensator condensed in four closely set end to end parts 6 swung on a common axis all arranged 30 and adjusted additionally to the old style single long compensator 5 which alone has proven, unsuccessful on a wide sheet of coloro-gravure.

As the full width sheet runs over the long compensators 5, which alone failed to register color perfectly, a set of slitters (not shown) is quickly put into operation dividing the sheet into four web strips. This is midway between the roll of paper and the 40 first impression cylinder. With the proper feed of the drums, proper tension of the roll, impressions and other devices about the press the sheet now operating in four parts will adjust itself naturally, eliminating wrinkles to a far greater extent than it has been in the past. A wide color sheet thus divided and run is much easier to control as each part can be given exact register. With the four color compensator each division of the 50 wide sheet is given the same attention throughout the entire color process and can be operated with one or more colors no matter how wide the main sheet may be. These devices can be applied and adjusted on all web presses, as for comics or rotogravure presses doing magazine work and the like.

A set of four color compensators 6 is adjusted between each color cylinder 1 and preceding long compensators 5, one set before the yellow, red, blue and black cylinders respectively. When starting on a new run the slitters are up and the sheet runs full over the shift cylinders and long compensators, the usual old way until the color fits the 60 closest. The next step is to lock the clutches

22 or 40 against the arms 12 on the sides of the roller 5 to allow no vibrations. All this occurs while the indicators have been moving back and forth by the movements of the compensators until the compensator 5 is set 70 on its perfect degree and it must remain in its original mark until the run is off.

Another important feature about this system relates to economy, and is that a sheet can never be entirely broken in the press. 75 Only part of it can be lost on account of bad paper, and when part of a sheet does break, the remedy is to raise the slitters and let the sheet run full, then taper it and paste the lead on either side of the other sheets, then move the press slowly until the broken sheet is in the folder. It only remains to lower the slitters and start off again.

I want to make this clear that my multiple webs are supplied from one main roll which is divided into four strips, running edge to edge throughout the press, into the folder. In reference to the main web which is divided in four strips from one large roll, it continues on its course with the narrow webs edge to edge from one unit to a succession of other units and into the folder. It would not be practical to run these webs from separate sources, for the reason that it would be necessary to take up much more room, require different spindles and different tension spring rollers, and would require frequent adjustment. For instance, if we should use a plurality of wholly separate webs supplied from a plurality of main rolls, one roll would unwind or fasten quicker than another one, and we would have to stop the press. With this new way, all the four webs are supplied from one main roll, and hence when the one roll unwinds it is only necessary to make 100 one stop to start a new one.

Although only two specific embodiments of this invention are herein shewn and described, it is to be understood that no attempt has been made to show all practical forms of embodiment and that some of the details of the constructions shown may be altered or omitted without departing from the spirit of this invention as defined by 110 the following claims.

I claim:

1. In a multiple web printing press, a set of compensating rolls, one for each web, disposed substantially end to end whereby the webs may be run approximately edge to edge, said press including a plurality of axially aligned rocker shafts for said rolls respectively and each roll being in combination with a pair of coaxially supported arms spaced apart less than the length of the corresponding roll and the roll being of axially sectional structure to accommodate such restricted spacing of the arms therefor. 120

2. In a multiple web press, a plurality of 130 axially aligned rocker shafts, compensator

rolls secured revolubly to said shafts respectively, a rotary hand rod for adjusting the angular position of each of said shafts respectively, and intermediate means connecting each shaft and corresponding rod respectively, the said intermediate means for the outermost shafts each including a bevel gear, and the corresponding means for the intermediate shafts each including a pair of 10 coating pinion gears and a secondary shaft operatively connected to the corresponding rocker shaft by said pinion gears.

3. A compensator roll comprising a central core and a three part cylindrical face

part disposed in coaxial alinement on said core, the middle face part being removable.

4. In a multiple web printing press, a main compensator roll over which all of the webs pass, and a plurality of short compensator rolls, one for each web, said main roll being mounted to oscillate revolubly about a fixed axis and having arms whereon it swings, in combination with damping means bearing against said arms in a direction parallel with the axis of said roll.

Signed at Chicago this 19th day of November 1924.

EDWARD A. WALLER.
